UNITED STATES PATENT OFFICE.

GEORGE H. HOUGHTON, OF ALBANY, NEW YORK.

SURGICAL SUPPORT FOR INJURED ARMS.

1,100,483.

Specification of Letters Patent. Patented June 16, 1914.

Application filed March 24, 1911. Serial No. 616,560.

To all whom it may concern:

Be it known that I, GEORGE H. HOUGHTON, a citizen of the United States of America, residing at No. 61 Eagle street, in the 5 city of Albany, in the county of Albany and State of New York, have invented certain new and useful Improvements in Surgical Supports for Injured Arms, of which the following is a specification.

10 My invention relates to surgical supports for injured arms, and the object of my invention is to provide a means for supporting and holding in proper position a fractured forearm or wrist, with a means for adjusting 15 the same; together with such other elements and combinations as are hereinafter more particularly set forth and claimed. I accomplish these objects by means of the mechanism illustrated in the accompanying 20 drawing, in which:

Figure 1 is a plan. Fig. 2 a side elevation. Fig. 3 an inverted plan view.

Similar letters refer to similar parts throughout the several views.

25 My arm support is preferably composed of two like portions, A, B, arranged side by side, as shown in Figs. 1 and 3, and held together along the adjoining edges, a, b, of the two like portions, A, B, by means of the 30 right and left screws, D, E, engaging with suitable ears, d, e, as shown in Fig. 3. By the operation of the screws, D, E, the parts may be drawn toward or separated from 35 each other, depending upon the direction of the rotation of said screws. About midway between the screws, D, E, I preferably place the set screw, F, mounted in the ear, f, on one of the like portions, B, the end of the screw, F, engaging with the block, G, in

40 the opposite portion, A, of the support. By means of this set screw F any looseness that may exist between the parts or members A and B, may be taken up and the two parts held rigidly in adjusted position. Each of 45 the portions, A, B, is raised and flared slightly outwardly, or dished, along a line parallel with its longitudinal axis so that the edge, H, of the portion, A, is raised above and over the main portion of the part,

50 A, as shown in Figs. 1 and 2. In like manner the edge, J, of the portion, B, is raised so that when placed in position the outer edges, H, J, of the support are raised above the main body thereof, forming a trough 55 into which the forearm and wrist of the

patient may be placed, the sides of the trough engaging the sides of the arm. One end of each portion, A, B, is depressed or bent downward, as at L, as shown in Figs. 1 and 2 particularly, forming a rest for the 60 palm of the hand and a portion of the fingers, the ends of the fingers preferably hooking over the ends, M, M, of the portions, A, B. The curvature of the depressed portion, L, is of a width and shape to conform to the hand in its natural position when hand, wrist and forearm are laid in the support, the hand placed palm downward into the depressed portion, L. The support is narrower at the wrist supporting 65 part to conform to the narrower space necessary to hold the wrist. The sides, H, J, engage the sides of the wrist and arm and hand and hold them positively in position. The knobs or pins, P, P, near one end of the 70 support are to engage with the plaster, not shown, used to hold the arm in place in the support.

75 My support is preferably constructed of some light metal, such as aluminum, although I do not limit myself to the material which may be used.

80 The support is constructed preferably from a mold in plaster of the forearm, wrist and hand laid into plaster, making an 85 anatomical specimen exact in every particular.

90 It is understood that the support is secured to the arm by suitable bandages, plaster or in any suitable manner.

95 I have illustrated and described my invention as composed of two portions adjustably secured together, but I do not wish to limit myself to this construction, since I may make the support of one piece and adjust the size to the arm to be fitted, using, where it may be properly done, a packing along the side between the arm and the sides of the support.

100 What I claim as my invention and desire to secure by Letters Patent is:

1. A splint for fractured limbs consisting of a trough-like structure divided longitudinally into two sections, means for connecting said sections whereby they may be adjusted toward and from each other, and means for holding the parts rigidly in adjusted position whereby the limb may be clamped with a constant unyielding lateral pressure.

2. A splint for fractured limbs consisting of a trough-like structure divided longitudinally into two sections, means for connecting said parts whereby the parts may be 5 adjusted toward and from each other, and means located intermediate the connecting means for holding the parts rigidly in adjusted position whereby the limb may be

clamped with a constant unyielding lateral pressure.

In testimony whereof I have affixed my signature in presence of two witnesses.

GEORGE H. HOUGHTON.

Witnesses:

LOTTIE PRIOR,
BEULAH COILE.
